COMBINATION GAME

Rose Urban, New York, N. Y.

Application October 9, 1947, Serial No. 778,825

5 Claims. (Cl. 273—58)

1

This invention relates to a combined device having a ball of spherical shape and constructed in hollow sections, so that a plurality of different field games may be played, by using the assembled unit or device, or by taking apart the sections of which the unit is constructed.

An object of the invention is to provide a hollow play ball which can be used for any field game for which it is suited, with a net holding ring which may be supported on a field for catching a ball of appropriate size, by removing a base section enclosed by the hollow ball.

A further object of the invention is the provision of a net holding ring, which can be clamped between the sections of the hollow play ball, with means for resiliently holding a net in position within the ring, so that balls may be thrown or projected toward the net in game playing action.

A still further object of the invention is to provide a hollow ball comprising separable sections with a coupling ring for securing the sections in spherical relation to each other, and a net holding ring which is clamped in immovable position between the coupling ring and one of the ball sections.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevation of the improved combination play ball.

Fig. 2 is a central sectional view taken on the line 2—2 of Fig. 1.

Fig. 3 is an edge elevation of one of the play discs, removed from the hollow ball.

Fig. 4 is a plan view thereof.

Fig. 5 is a perspective view showing one of the interior hollow ball sections used as a base for a net holding ring.

Fig. 6 is a vertical sectional view taken on line 6—6 of Fig. 5, looking in the direction of the arrows, showing the resilient rubber net holding ring in the supporting metal ring.

Fig. 7 is a bottom plan view of the hollow base, showing suction cups thereon for securing the base and the net against sliding on a rubber tile or glazed tile or smooth field surface.

Fig. 8 is a side view of the rubber ring and supporting metal ring.

Referring to the drawings, which illustrate the

2

practical embodiment of the invention, 10 designates a sectional hollow play ball, of true spherical construction, which may be used as an assembled unit to play various games of field ball, and which may be constructed of processed wood, plastic, or a combination of plastic and other materials.

The ball 10 includes the hollow sections 11 and 12, which are connected to each other by the coupling ring 13, which is provided with an intermediate annular portion 14 which forms the joint between the inner faces of the hollow ball sections 11 and 12, and which is connected with the internally screw threaded portion 15, which has coupling engagement with the ball section 11, and is connected with the externally screw threaded portion 16, which has coupling engagement with the ball section 12.

A net holding ring 17 of channel construction, 20 is clamped between the coupling ring 13 and one of the ball sections, and with the two ball sections and the coupling ring 13, completes the ball form.

Within the hollow ball sections and the rings 13 and 17 two play discs 18 and 19 are disposed. These discs are of generally circular and flat construction, and are provided with a grooved peripheral edge 20, which snugly receives the resilient rubber tire 21, which extends outwardly of the peripheral edge, to have snug pressure engagement with the inner surfaces of the sectional ball 10.

The ball sections 11 and 12 are formed with openings 11^a and 12^a for supporting a suitable croquet arch for playing the game.

35 The two play discs 18 and 19 are disposed in contact with each other at the center of the hollow ball construction, and the outer face of the disc 18 is engaged by the hollow ball section 22, which is equipped with suction cups 24 on its chordal inner face or edge 23, which have pressure engagement with the disc 18. The outer face of the disc 19 is engaged by the suction cups 24 of the hollow ball section 26.

40 The play disc 18 is formed with a center opening 18^a, to receive the end of a play bat or shank, and the play disc 19 is formed with a similar center opening 19^a for a similar purpose.

The hollow interior ball section 22 is formed with a centrally located slot 27, designed to receive the net holding ring 17, and the hollow ball section 26 is formed with a similar central slot 28 to receive such ring 17.

45 The ring 17 is formed with an internal annular groove 17^a, in which the rubber ring 29 is placed.

This rubber ring is provided with a fabric ball net 30, the forward edge of which is suitably bonded to the rubber holding ring 29 by vulcanization or otherwise.

The rubber holding ring 29 and the fabric ball net 30 may be collapsed inside of one of the hollow ball sections 22 or 26, or kept outside of the play ball 10.

The combined device thus provides means for playing various field ball games, such as foot ball, hand ball, pitching, medicine ball, when the assembled unit is used as a single device.

By separating the outer ball sections from each other, the net holding ring may be removed, a net is placed in this ring, and then this ring and net assembly are supported on a field by one of the hollow interior ball sections. Field croquet may then be played using this vertically supporting net holding ring, and various other field ball games may be played, including field golf or a modified form thereof, in which play action is developed by an effort to project a ball by a suitable club or bat into the net.

The play discs may be used in playing croquet and other types of field games, in which objects are pushed around in competition between players over a marked field, and play points are gained by positions gained in such competition.

In playing miniature golf, the hollow interior ball sections may be used for marking positions and establishing hazards over route courses.

It will be seen from the foregoing that there is combined in a single assembled unit, a device which serves to play various games of field ball, and that when taken apart the enclosed sections are adapted for use in various other field games, in connection with game devices which need not be here shown.

The net 30 may be omitted and the ring 17 used as a confining path for the projection of any ball used in any field game suitable for such use.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In a game device, a hollow ball formed of an opposed pair of substantially hollow semi-spherical ball portions, a coupling ring interposed between said ball portions separably joining them together, a ring for a net supported between an undercut portion of one of said ball portions and the adjacent side of said coupling ring, opposed cups within said ball portions, said cups being formed on their outer sides opposed to their open sides with centrally located slots, whereby when said ball portions are separated from said coupling ring one of said cups can be removed and rested on a flat surface with its slot uppermost to receive a peripheral edge portion of said latter-mentioned ring to support the same in a vertical plane.

2. In a game device, a hollow ball formed of an opposed pair of substantially hollow semi-spherical ball portions, a coupling ring interposed between said ball portions joining them together, a ring for a net supported between one of said ball portions and the adjacent side of said cou-

pling ring, opposed cups within said ball portions, said cups being formed on their outer sides opposed to their open sides with centrally located slots, whereby when said ball portions are disengaged from said coupling ring one of said cups can be removed and rested on a flat surface with its slot uppermost to receive a peripheral edge portion of said latter-mentioned ring to support the same in a vertical plane, said latter-mentioned ring having an outside diameter corresponding to the outside diameter of said hollow ball and said one ball portion being undercut to receive and support said latter-mentioned ring in the assembled condition of said ball.

3. In a game device, a hollow ball formed of an opposed pair of substantially hollow semi-spherical ball portions, a coupling ring interposed between said ball portions separably joining them together, a ring for a net supported between an undercut portion of one of said ball portions and the adjacent side of said coupling ring, opposed cups within said ball portions, said cups being formed on their outer sides opposed to their open sides with centrally located slots, whereby when said ball portions are disengaged from said coupling ring one of said cups can be removed and rested on a flat surface with its slot uppermost to receive a peripheral edge portion of said latter-mentioned ring to support the same in a vertical plane, said separable joining of said coupling ring and said ball portions comprising a reduced internally threaded portion formed on one side of said coupling ring and engaging an externally threaded portion formed on the said one ball portion, and a reduced externally threaded portion formed on the other side of said coupling ring and engaging an internally threaded portion formed on the other of said ball portions.

4. In a game device, a hollow ball formed of an opposed pair of substantially hollow semi-spherical ball portions, a coupling ring interposed between said ball portions joining them together, a ring for a net supported between one of said ball portions and the adjacent side of said coupling ring, opposed cups within said ball portions, said cups being formed on their outer sides opposed to their open sides with centrally located slots, whereby when said ball portions are disengaged from said coupling ring one of said cups can be removed and rested on a flat surface with its slot uppermost to receive a peripheral edge portion of said latter-mentioned ring to support the same in a vertical plane, a reduced internally threaded portion formed on one side of said coupling ring and engaging an externally threaded portion formed on one of said ball portions, and a reduced externally threaded portion formed on the other side of said coupling ring and engaging an internally threaded portion formed on the other of said ball portions, said latter-mentioned ring being supported on said one ball portion adjacent the internally threaded portion of said coupling ring.

5. In a game device, a hollow ball formed of an opposed pair of substantially hollow semi-spherical ball portions, a coupling ring interposed between said ball portions joining them together, a ring for a net supported between one of said ball portions and the adjacent side of said coupling ring, opposed cups within said ball portions, said cups being formed on their outer sides opposed to their open sides with centrally located slots, whereby when said ball portions are disengaged from said coupling ring one of said

cups can be removed and rested on a flat surface with its slot uppermost to receive a peripheral edge portion of said latter-mentioned ring to support the same in a vertical plane, said latter-mentioned ring being formed of continuous channel-shaped material having its open side directed inward, and a net for use with said latter-mentioned ring disposed within one of said cups in the assembled condition of said hollow ball, comprising a continuous rubber ring adapted to be inserted into said latter-mentioned ring from the inside thereof, and a fabric ball net having its open edge portions vulcanized in said rubber ring.
